A. COCOZELLA

HEEL

Filed Nov. 28, 1925

UNITED STATES PATENT OFFICE.

ANTHONY COCOZELLA, OF LYNN, MASSACHUSETTS, ASSIGNOR, BY DIRECT AND MESNE ASSIGNMENTS, TO UNITED SHOE MACHINERY CORPORATION, OF PATERSON, NEW JERSEY, A CORPORATION OF NEW JERSEY.

HEEL.

Application filed November 28, 1925. Serial No. 71,989.

This invention relates to improvements in shoes and heels and to improvements in the art of making shoes and heels. As herein illustrated the invention is particularly concerned with the covering of the breast surfaces of wooden Louis heels and with the preparation of the heels for the reception of the breast coverings.

In accordance with the usual practice the breasts of Louis heels are covered by thin flaps of leather which are split from the outer or grain sides of the soles of shoes to which the heels are attached. These flaps are trimmed to fit the heel breasts and the margins of the flaps are often skived or beveled to produce feather edges. When secured in place the trimmed feather edges of the flaps are flush with the side faces of the heels and are liable to become separated more or less from close contact with the heels as the shoes are worn, or to be loosened by careless or repeated handling of the shoes even before the shoes are worn. If, as in some of the cheaper grades of shoes, the edges of the breast flaps are not made thin by skiving, the unskived edges detract from the appearance of the shoe because of the noticeable difference in tone and texture between these edges and the burnished grain surface on the exposed side of the breast flap.

One object of the present invention is to avoid the unsatisfactory conditions above referred to and with this object in view one feature of the invention consists in the provision of a heel having a recess in its breast surface for the reception of a covering such as a flap split from the sole of a shoe, the recess being of less width than the breast face of the heel so that the covering may be fitted within the recess with the opposite edges of the covering hidden from view and protected by heel material at the opposite sides of the recess, and a pleasing paneled effect obtained. As shown, this protecting material is in the form of relatively narrow ribs and the heels are covered in the usual manner by suitable material such as celluloid which overlaps the ribs and is trimmed flush with the inner edges of the ribs. Also, as shown, the opposite lateral edges of the sole flap are shaped to abut the inner edges of the ribs and the trimmed edges of the overlapping portions of the heel cover, and the recess is of such

depth that the exposed face of the flap is flush with the outer surface of the covering on the ribs. The invention is not necessarily limited, however, to a construction in which the portions of the heel cover which overlap the ribs are trimmed flush with the inner edges of the ribs.

In another aspect the invention comprises making a heel with a recess in its breast surface, attaching the heel to a shoe, and covering the recessed portion of the breast surface of the heel by a flap split from the sole of the shoe. The invention is not necessarily limited, however, to the use of a flap integral with the sole of the shoe to which the heel is attached nor to the attaching of the heel to the shoe before the covering is applied to the heel breast since in some cases it may be desirable to cover the recessed breast surfaces of an unattached heel by a covering which preferably will extend more or less beyond the edge at the junction of the breast and the seat face of the heel for attachment to the shank portion of the sole after the attachment of the heel to the shoe. In another aspect, therefore, invention is to be recognized in making a heel with a depression or recess in its breast surface and covering the depressed portion of the breast surface.

The invention will be explained with reference to the accompanying drawings, in which

Fig. 1 is a perspective view of a lady's shoe provided with a Louis heel the breast of which has been prepared and covered in accordance with the present invention;

Fig. 2 is a fragmentary view, partially in section, of the shoe shown in Fig. 1;

Fig. 3 is a sectional view taken on the line 3-3 of Fig. 2;

Fig. 4 is a sectional view taken on the line 4-4 of Fig. 2, crosshatching being omitted for clearness of illustration;

Fig. 5 is a cross-sectional view of the heel shown in Fig. 4, crosshatching being omitted for clearness; and

Fig. 6 is a cross-sectional view, similar to Fig. 5, illustrating the usual method of arranging the heel covers, crosshatching being omitted for clearness.

Referring to the drawings, 10 indicates a wooden Louis heel or heel block, as a wood heel is commonly called before it is covered,

and 11 indicates a covering of celluloid for the rear and side surfaces of the heel. This covering 11, which may be of other material than celluloid, such for example as fabric or leather, has its lateral margins at the front of the heel turned inwardly, as shown at 15, to overlap the opposite edge portions of the breast surface of the heel. A leather flap or leaf 12 split from the rear of the sole 13 of 10 a shoe to which the heel is attached is secured to the breast of the heel between the inturned portions 15 of the covering 11.

Ordinarily a heel breast covering flap is considerably thicker than the covering for 15 the rest of the heel and in order that the breast flap 12, after being laid against the heel breast, shall be disposed with its outer surface flush with the outer surfaces of the inturned portions 15 of the covering 11, the 20 heel block 10 is made with a shallow recess or depression 14 extending from the top to the bottom of the heel breast. This recess 14 is preferably made as deep as the thickness of the breast flap minus the thickness of the 25 heel covering in order to obtain the desired flush relation of the exposed surfaces of the flap and the inturned margins of the heel covering. As shown, the width of the recess 14 is less than the full width of the heel so 30 that relatively narrow ribs 16 are formed adjacent to the opposite lateral edges of the heel breast. The ribs 16 and the recess 14 may be formed by cutting away or otherwise 35 removing material from the breast of the heel or they may be formed by building up the 40 marginal portions of the heel breast.

Before the heel is attached to the shoe the covering 11 is applied to the rear and sides of the heel in the usual manner, the top and 45 bottom edges of the covering being turned inwardly against the seat and top-lift engaging faces, respectively, of the heel block. The lateral edge portions of the heel covering are then turned inwardly from the positions indicated by dotted lines at 15^x in Fig. 5 to form cover flaps 15 arranged in close contact with the top faces of the ribs 16, as shown at 15 in Fig. 5.

In the process of turning the edge portions 50 or flaps 15 of the heel cover well-known methods are employed to secure pliability of the celluloid, if that is the material employed for the cover, so that when the cover flaps are brought into contact with the ribs 16 they 55 will tend to remain in such position irrespective of whether or not adhesive is employed. It is preferred, however, to use adhesive for securing both the flaps 15 as well as the body portion of the cover in place.

In case the cover flaps 15 are wider than 60 necessary to cover the rear faces of the ribs 16, or if the flaps are ragged at their edges, the ragged or excess material is trimmed off, the inner edges of the ribs serving as suitable 65 gages for the trimming tool to insure smooth

and accurate trimming of the cover flaps so that the trimmed edges will be flush with the inner edges of the ribs. After the above operations have been performed in connection with the covering of the rear and sides of 70 the heel, as well as the covering of the ribs 16, a top lift 17 will be applied and the heel will be assembled with the shoe and either temporarily or permanently attached thereto but prior to the assembling of the heel with 75 the shoe the flap 12 of the sole 13 will be turned backwardly to expose the fitted heel-seat portion of the sole.

After the heel has been attached adhesive is applied to the inner surface of the sole 80 flap 12. The flap 12 has the same marginal outline as the heel portion of the sole from which it was split and before the flap can be fitted within the recess 14 in the breast of the heel the flap must be trimmed to fit the 85 recess. This trimming of the breast flap preferably takes place after the adhesive has been applied and the middle portion of the flap has been pressed into place against the heel breast at least sufficiently to hold the 90 flap against edgewise displacement relatively to the heel while it is being trimmed. This procedure renders it practicable to employ the inner sides of the ribs 16 of the heel as gages for the trimming tool 95 so as to insure that the trimmed edges of the flap will fit accurately in butting relationship with the inner sides of the ribs 16 and the inner edges of the heel cover flaps 15 which overlap the ribs. After being trimmed the margins of the breast flap will be pressed firmly into the recess in the heel, care being taken to secure the desired close butted joints between the adjacent edges of the breast flap and the cover flaps 15 and the desired flush 100 relation of the exposed surfaces of the breast and cover flaps. The breast flap then constitutes a cover panel framed by the covered ribs 16. It will be noted that inasmuch as the opposite edges of the breast flap are unexposed it is unnecessary to skive or bevel the edges as heretofore in order to impart a 105 finished appearance to the shoe.

Fig. 6 of the drawings shows a wooden heel 110 which has been covered in the usual manner, the covering 11^x for the rear and sides of the heel having been trimmed off at the opposite edges of the face and the breast flap 12^x extending the full width of the heel breast. With such an arrangement both the trimmed edges of the heel cover and the trimmed edges of the breast flap are unprotected and exposed to influences tending to separate them from contact with the heel. Such an arrangement of the breast flap also tends to incite a desire on the part of a person examining or handling the shoe to test the condition of the edges of the flap with the result that frequently the flap or at least the edges thereof becomes loosened or injured and the shoe has 115 120 125

to be repaired. Fig. 5 shows the positions of the edges 20 of the heel covering relatively to the edges or corners 21 of the heel, the edges 20 being spaced inwardly from said corners and being flush with the shoulders or faces at the inner sides of the ribs 16. When the breast flap has been secured in place within the recess 14, as shown in Fig. 4, not only will it protect the inturned edges of 10 the heel cover 11 but the edges of the heel cover and the inner sides of the ribs 16 will protect the edges of the breast flap. With this improved construction there is no temptation to pry at the edges of the breast flap 15 and the breast flap is prevented from becoming loosened or separated from the heel. Moreover, the neatness and general attractiveness of the heel are increased and there is imparted to the shoe a finished appearance 20 which is lacking when the trimmed edges of the breast flap extend to the extreme edge portions of the heel breast as heretofore.

Having described my invention, what I claim as new and desire to secure by Letters 25 Patent of the United States is:—

1. A shoe heel having a cover extending around its rear and side faces and overlapping the lateral margins of its breast face, and having a recess formed in its body portion between said overlapping portions of said cover to receive a breast covering.

2. A shoe heel comprising a heel block having its breast recessed to provide raised lateral edge portions and a shallow depression 35 between said raised portions, a cover panel fitting within and filling said depression, and a covering for the rear and sides of the heel having lateral margins overlapping the raised lateral edge portions at the breast of 40 the heel block and abutting the edges of said cover panel.

3. An article of manufacture comprising a shoe heel, a cover for said heel composed of thin material and arranged to overlap the 45 breast at the side edges thereof in such manner as to be exposed to view, the said heel having a shallow recess in the breast extending from the top to the bottom which has sharply defined walls with which the edges of the overlapped thin material are flush; a covering of 50 comparatively thick material arranged to be embedded in said recess and with its edges snugly abutting said walls and the edges of the said thin material, and with its exposed 55 face flush with that of the said thin material.

4. As an article of manufacture a heel having a convex portion at the breast thereof, said portion extending from the top to the bottom of said breast, and laterally to points adjacent 60 the side edges thereof, the lateral terminals of said convex portion being below the marginal edges of said breast whereby defined receptacles for the marginal edges of a cover for said breast are formed.

5. As an article of manufacture, a shoe heel

having in its body portion a depression in the breast thereof for the reception of a breast cover, said depression extending downwardly from the top of said breast and laterally to surfaces spaced inwardly from the side edges 70 of said breast.

6. As an article of manufacture, a heel block having ribs formed one at each lateral margin of its breast and projecting beyond its breast surface, said ribs extending from the 75 top to the bottom of the breast to protect the lateral edges of a breast covering to be fitted between them.

7. The combination in a shoe, of a wooden Louis heel having at each lateral margin of its breast a rib projecting beyond the breast surface, a covering for the rear and sides of the heel having inturned portions overlapping said ribs, and a breast covering flap split from the sole of the shoe and shaped 80 to fit within the cavity between said ribs, the height of the ribs being predetermined with reference to the thickness of the breast flap and the heel covering to insure that the exposed surface of the breast flap will be flush 85 with the outer surfaces of said overlapping portions of the heel covering.

8. That improvement in the art of making shoes which consists in making a heel with a recess in its breast surface, attaching the heel to a shoe, and covering the recessed portion of the breast surface of the heel by a flap split from the sole of a shoe.

9. That improvement in the manufacture 100 of shoes which consists in making a heel with a depression in its breast surface, and covering the depressed portion of said breast surface and the joint between said surface and the sole of a shoe to which the heel is attached.

10. That improvement in the manufacture 105 of shoes which consists in making a heel with depressed portions extending downwardly from the top of the heel breast and forming ribs at the lateral edges of the breast, and fitting a breast covering within said depressed portions of the heel breast with the edges of said covering abutting against said ribs.

11. That improvement in methods of making heels which consists in forming ribs one 115 at either lateral edge of the breast of a heel block, said ribs projecting beyond the adjacent portion of said breast surface, and covering the breast surface between said ribs.

12. That improvement in methods of 120 finishing heels which consists in cutting away material from the heel to form a recess in its breast surface and fitting a covering within said recess with the exposed surface of the covering flush with the unrecessed surface of the heel breast.

13. That improvement in the art of making 125 shoes which consists in providing a recess in the breast of a heel to receive a breast covering flap, attaching the recessed heel 130

to a shoe having a sole the rear portion of which has been split to form a heel breast covering flap integral with the sole, shaping the sole flap to fit within the recess in the 5 heel, and securing the flap in place within the recess.

14. That improvement in the art of finishing heels which consists in recessing the breast of a heel to provide a cavity for the 10 reception of a breast covering and to provide ribs one at each side of the cavity to protect the edges of the breast covering, applying to the rear and sides of the heel a covering adapted to project beyond the edges of the 15 heel breast, turning inwardly said projecting portions of said heel cover against the top surfaces of the ribs on the heel breast, and trimming the edges of the inturned portions of the heel cover which extend beyond 20 the inner sides of said ribs.

15. That improvement in the art of finishing heels which consists in recessing the breast of a heel to provide a cavity for the reception of a breast covering and to provide 25 ribs one at each side of the cavity to protect

the edges of the breast covering, applying to the rear and sides of the heel a cover adapted to project beyond the heel breast, turning the projecting portions of said heel cover inwardly to overlap the ribs on the heel 30 breast, and utilizing the inner sides of said ribs as gages in trimming off the edges of the heel cover which extend beyond the ribs. 35

16. That improvement in methods of making shoes which consists in providing a recess in the breast of a heel, attaching the recessed heel to a shoe having a sole the rear portion of which has been split to form a heel breast covering flap integral with the sole; applying adhesive to the sole flap, partially attaching the sole flap within the recess in the breast face of the heel to prevent edgewise displacement of the flap relatively to the heel, trimming the flap to fit the recess in the heel while the flap is held against edgewise displacement, and completing the attachment of the 40 sole flap to the heel. 45

Signed by me at Boston, Massachusetts, this 23rd day of November, 1925.

ANTHONY COCOZELLA.
